(57) **CLAIM**

The ornamental design for a bar of soap, as shown and described.

DESCRIPTION

FIG. 1 is a front top perspective view of a bar of soap with three circular-shaped apertures extending there through, according to an example embodiment of the present disclosure.

FIG. 2 is a front view of the bar of soap illustrated in FIG. 1.

FIG. 3 is a rear view of the bar of soap illustrated in FIG. 1, showing that the front view is a mirror image of the back view.

FIG. 4 is a left side view of the bar of soap illustrated in FIG. 1.

FIG. 5 is a right side view of the bar of soap illustrated in FIG. 1, showing that the left side view is a mirror image of the right side view.

FIG. 6 is a top view of the bar of soap illustrated in FIG. 1; FIG. 7 is a bottom view of the bar of soap illustrated in FIG. 1, showing that the top view is a mirror image of the bottom view.

FIG. 8 is a front top perspective cross-sectional view of the bar of soap illustrated in FIG. 1, showing the three circular-shaped apertures extending from the front to the back.

FIG. 9 is a front view of the second embodiment of the bar of soap, with four circular-shaped apertures extending there through.

FIG. 10 is a front view of the third embodiment of the bar of soap, with five circular-shaped apertures extending there through.

FIG. 11 is a front view of the fourth embodiment of the bar of soap, with three oval-shaped apertures extending there through. The top, bottom, and side views being identical to the first embodiment.

FIG. 12 is a cross sectional view of the fourth embodiment of the bar of soap, with three oval-shaped apertures extending there through.

(Continued)

FIG. 13 is a front view of the fifth embodiment of the bar of soap, with four oval-shaped apertures extending there through; and,

FIG. 14 is a front view of the sixth embodiment of the bar of soap, with five oval-shaped apertures extending there through.
